(57) CLAIM

The ornamental design for a light fixture, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top, right, perspective view of a light fixture showing our new design;

FIG. 2 is a front, top, left, perspective view thereof;

FIG. 3 is a front, bottom, right, perspective view thereof;

FIG. 4 is a front, bottom, left perspective view thereof;

FIG. 5 is a back, top, right, perspective view thereof;

FIG. 6 is a back, top, left, perspective view thereof;

FIG. 7 is a back, bottom, right, perspective view thereof;

FIG. 8 is a back, bottom, left, perspective view thereof;

FIG. 9 is a front side view thereof;

FIG. 10 is a back side view thereof;

FIG. 11 is a right side view thereof;

FIG. 12 is a left side view thereof;

FIG. 13 is a top view thereof;

FIG. 14 is a bottom view thereof;

FIG. 15 is a front, top, right, perspective view of another embodiment a light fixture showing our new design;

FIG. 16 is a front, top, left, perspective view thereof;

FIG. 17 is a front, bottom, right, perspective view thereof;

FIG. 18 is a front, bottom, left perspective view thereof;

FIG. 19 is a back, top, right, perspective view thereof;

FIG. 20 is a back, top, left, perspective view thereof;

FIG. 21 is a back, bottom, right, perspective view thereof;

FIG. 22 is a back, bottom, left, perspective view thereof;

FIG. 23 is a front side view thereof;

FIG. 24 is a back side view thereof;

FIG. 25 is a right side view thereof;

FIG. 26 is a left side view thereof;

FIG. 27 is a top view thereof; and

FIG. 28 is a bottom view thereof;

FIG. 29 is a front, top, right, perspective view of another embodiment a light fixture showing our new design;

FIG. 30 is a front, top, left, perspective view thereof;

FIG. 31 is a front, bottom, right, perspective view thereof;

FIG. 32 is a front, bottom, left perspective view thereof;

FIG. 33 is a back, top, right, perspective view thereof;

FIG. 34 is a back, top, left, perspective view thereof;

FIG. 35 is a back, bottom, right, perspective view thereof;

FIG. 36 is a back, bottom, left, perspective view thereof;

FIG. 37 is a front side view thereof;

FIG. 38 is a back side view thereof;

FIG. 39 is a right side view thereof;

FIG. 40 is a left side view thereof;
FIG. 41 is a top view thereof; and,
FIG. 42 is a bottom view thereof.
